UNITED STATES PATENT OFFICE.

CARL MEIER, OF NEU-RUPPIN, GERMANY.

PEDAL MECHANISM FOR BICYCLES OR THE LIKE.

SPECIFICATION forming part of Letters Patent No. 613,456, dated November 1, 1898.

Application filed May 6, 1897. Serial No. 635,438. (No model.)

To all whom it may concern:

Be it known that I, CARL MEIER, a subject of the King of Prussia, German Emperor, residing at Heinrichstr. 1, Neu-Ruppin, Prussia, Germany, have invented a certain new and useful Improvement in Pedal Mechanisms for Bicycles and the Like, (for which I have received patents in England, dated May 8, 1897, No. 7,442; in France, dated June 29, 1897, No. 265,253; in Belgium, dated April 15, 1897, No. 127,146; in Italy, dated May 24, 1897, No. 44,194, and in Canada, dated July 28, 1897, No. 56,832,) of which the following is a specification.

My invention relates to a new and useful improvement in pedal mechanisms for bicycles and the like, and has for its object to provide means whereby the path described by the pedal will be eccentric relative to the crank-shaft, thus increasing the leverage upon one side of said shaft, while decreasing it upon the reverse side, and in the several embodiments of my invention this is accomplished by causing the pedals to either travel in an elliptical or irregular path, which will bring the pedals in a most advantageous relation to the crank-shaft when force is being applied thereon.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, forming a part of this specification, in which—

Figure 1 is a side view of one form of my invention, the broken line representing the path of the pedal. Fig. 2 is a similar view of another embodiment of my improvement.

In carrying out my invention as shown in Fig. 1 the stationary gear *b* is secured concentric with the shaft *a* and an arm *c* secured upon said shaft, and a gear *f* is also journaled in one end of this arm, while a similar gear *f'* is journaled in the opposite end thereof. These two gears mesh with the stationary gear and when revolved about the latter ac-

complish two revolutions upon their axes for every revolution of the arm *c*, as is well understood. A short crank *g* is secured upon a short shaft *e*, upon which the gear *f* is secured, and revolves therewith, while a shorter crank *m* is secured upon the short shaft *d*, upon which the gear *f'* is secured, and revolves therewith. The pedal-crank is pivoted at *h* to the crank *g* and connected, by means of the stud *d'*, passing through the slot *s*, to the shorter shaft *m*. The result of this construction is that when the pedal-crank has revolved through the medium of the pedal *p* said pedal is caused to describe a slightly-elliptical curve, as shown in broken lines, on account of the difference in throw of the cranks *g* and *m* and a further fact that the crank *m* is attached to the pedal-crank by a slot, while the crank *g* is pivotally attached thereto.

The embodiment of my invention as illustrated in Fig. 2 contemplates the securement of a stationary gear *b* concentric with the crank-shaft *a*, and the arm *c* being secured to said shaft, in which are journaled the gear-wheels *f* and *f'*, as before set forth; but these gear-wheels have attached to their shafts *e* and *d* the short cranks *g* and *g'*, of equal length, while to these cranks is pivoted at *h* and *h'* the pedal-crank *r*, said crank being adapted to receive the pedal at the point *k*. Now, as is obvious, the revolving of the crank *r* will bring about the revolving of the arm *c*, and this in turn will cause the gear-wheels *f* and *f'* to rotate upon their axes, while at the same time revolving around the crank-shaft *a*, and, as already stated, this movement will cause the gear-wheels *f* and *f'* to rotate twice upon their axes for every complete revolution of the arm *c*, which will impart to the outer end of the pedal-crank a motion which will cause the point *k* to describe the path indicated by the broken line *x*.

Having thus fully described my invention, what I claim as new and useful is—

1. A crank mechanism for bicycles consisting of a crank-shaft, a stationary gear mounted concentric therewith, an arm mounted on the shaft, short shafts secured in the ends of the arm, gears on said shafts meshing with the first-named gear, cranks on the outer ends of the short shafts and a pedal-crank having

two arms extending therefrom each one being pivoted at its end to one of the cranks on the short shafts, substantially as described.

2. A crank mechanism consisting of a stationary gear, an arm rotatably mounted concentric with the gear, movable gears rotatably mounted on the ends of the arm meshing with the first-named gear, cranks provided on the last-named gears, a pedal-crank con-

nected with the cranks on the gears, as and for the purpose described.

In testimony whereof I hereunto set my hand in presence of two witnesses.

CARL MEIER.
